United States Patent Office.

ALEXANDER C. DECKER, OF BUSHNELL, ILLINOIS.

Letters Patent No. 76,172, dated March 31, 1868.

IMPROVED DITCHING-MACHINE.

The Schedule referred to in these Letters Patent and making part of the same.

TO ALL WHOM IT MAY CONCERN:

Be it known that I, ALEXANDER C. DECKER, of Bushnell, in the county of McDonough, and State of Illinois, have invented a new and improved Ditching-Machine; and I do hereby declare that the following is a full and exact description of the same, reference being had to the accompanying drawings, and to the letters of reference marked thereon.

This invention consists in an improved construction of a ditching-machine, by means of which the dirt is cut by a plough, and carried to one side, at a distance from the ditch, by means of a series of buckets attached to a belt; also, in certain novel devices for operating various parts of the machine, as will be hereinafter fully described.

Figure 1 represents a sectional view through the line x x , and

Figure 2 a top view of my machine.

In the drawings, A represents the main frame of the machine, supported upon the wheels a a and caster-wheel a' , to which frame is hinged the small frame B.

C C' represent longitudinal beams, between which the shovel D is suspended. C'' also represents a longitudinal beam, which, with the beam C', forms a support for the seat E.

F represents a shaft, hung in bearings upon the under side of the frame A, which shaft forms the axle for the wheels a , the latter revolving freely upon the former in one direction, but, when moved in a contrary manner, give motion to the shaft by means of a ratchet-wheel and pawl. The shaft F extends beyond the main frame upon the inner side, and is coupled in a suitable manner to the shaft G, which latter unites with shaft H of the wheel H'.

H' represents a bevelled gear-wheel, which operates the corresponding wheel I, upon whose shaft are placed flanged spur-wheels, by which latter means motion is given to the buckets J.

K, fig. 1, represents small wheels, in pairs, hung at suitable and regular intervals within the rear end of the main frame A, and within the small frame B, which, thus arranged, are designed to carry the buckets J.

L represents a flanged roller, supported in bearings, l l , beneath the main frame, the object of which is to support the buckets J, and prevent them from coming in contact with the ground.

M represents a belt of buckets, which may be constructed in any suitable manner or shape. In this case, the belt consists of alternate links of wire and sheet metal, the latter of which are attached to the buckets upon their under side, and the former of which, being open, are caught by the spurs upon the wheels of the driving-shaft.

The buckets J are constructed with three sides only, the upper side being left open, in order to facilitate the discharge of the dirt at the proper moment. A caster-wheel is attached at the point n , which supports the frame B.

The plough or shovel D is constructed, as shown in fig. 2, with the point d , which first enters the ground, and from which point to the point d' runs the cutting-line, this angle being most suitable for penetrating the earth easily. From this line the shovel slopes upward and rearward, by a gentle incline, until its rear end is over the buckets J. The shovel also is provided with suitable sides, so that the dirt, as fast as it is cut, is delivered to the buckets.

d'' , fig. 1, represents a shoe, attached to the under side of the plough D, by which means the latter is kept in proper line.

d^3 represents a flanged roller, to which is attached one end of the chains d^4 , the other end of which latter is attached to the sides of the shovel at a point near its upper end.

d^5 represents a similar roller and chains, the lower ends of which latter are attached to the arms d^6 , which branch forward and upward from the shovel D. These arms d^6 are provided, at the forward ends, with holes, d^7 , as shown in fig. 1.

R represents a slotted clevis, attached to the under side of the frame A, whose lower ends unite with the bars S. A rod, r , passes through slots in clevis, and through one pair of the holes d^7 , by which arrangement the shovel is properly guided when raised or lowered. By the use of the different holes d^7 , it may be adjusted forward or backward, as may be desired.

The rollers d^3 d^5 are actuated by levers, u u^1 , which are operated in connection with the racks u^2 u^3 .

To the bottom of the seat E are attached the rods e e , which pass through both the upper and lower bars of the standard e^1 , and are provided with heads upon the lower sides. e^2 e^3 represent springs, encircling the rods e . By this arrangement of rods and springs, the seat is rendered very secure, and, at the same time, extremely easy. The rods e prevent any lateral movement, and, at the same time, yield readily in a perpendicular direction, so that the entire weight of the driver rests upon the springs.

It will be observed that the frame A is constructed in such manner that the side upon which the plough is located is the lowest, the belt of buckets being an inclined plane.

The operation of my invention is as follows: The shovel having been first adjusted properly by means of the levers u u^1 , the machine is set in motion. The pawl upon the wheels α engaging with the ratchet-wheel upon the shaft F, motion is thus given to the latter, which, combining with gear-wheel I, by means of shafts G H and gear-wheel H', operates the buckets J. The dirt, rising from the plough, falls upon the buckets, and is delivered therefrom at a distance from the ditch.

The frame B being hinged to the frame A, and the shaft G being connected with the shafts F and H by universal joints, the frame B can be elevated or depressed, as desired; and the machine is thus enabled, by this arrangement, to pass readily over uneven ground.

The arrangement of ratchet-wheel and pawl allows the machine to be backed in any direction, when necessary, without operating the buckets.

This general combination and arrangement is believed to be more simple and compact than anything of the kind in use.

This machine is not only adapted for ditching, but can also be used for grading purposes, the earth being taken from the sides of the road, and delivered in the centre, or the contrary, as may be desired.

This machine may be made right or left-handed, as desired.

Having thus fully described my invention, what I claim as new, and desire to secure by Letters Patent, is—

1. The shovel D, constructed, as described, with cutting-edge d d^1 , arms d^6 , and shoe d^2 , in combination with clevis R, rod r , chains d^4 , rollers d^3 d^5 , levers u u^1 , and racks u^2 u^3 , substantially as described.

2. The frame A, constructed as described, frame B, buckets M, wheels K, and roller L, when combined and arranged as and for the purpose set forth.

3. The shaft F, shaft G, shaft H, wheel H', wheel I, with driving-shaft and spur-wheels, when combined and operated in the manner set forth.

This specification signed and witnessed, this fifteenth day of January, 1868.

A. C. DECKER.
